UNITED STATES PATENT OFFICE.

FREDERICK LYNN SHELOR, OF SALEM, VIRGINIA, ASSIGNOR TO INTERNATIONAL FILLER CORPORATION, OF RICHMOND, VIRGINIA.

BOTTLE-FILLING APPARATUS.

1,232,105.

Specification of Letters Patent.

Patented July 3, 1917.

Application filed February 2, 1916. Serial No. 75,797.

To all whom it may concern:

Be it known that I, FREDERICK LYNN SHELOR, a citizen of the United States, residing at Salem, in the county of Roanoke and 5 State of Virginia, have invented a new and useful Bottle-Filling Apparatus, of which the following is a specification.

The present invention appertains to bottle filling apparatus, and aims to provide a 10 novel and improved bottle filling apparatus which has a wide range of use, the same being adapted for use in connection with various liquids, and upon various bottles and similar vessels, and the component parts 15 being readily disassembled for purpose of cleaning, repair or replacement.

It is the object of the invention to provide a bottle filling apparatus which can be conveniently manipulated or applied to and removed from the bottles, and which has a 20 novel nozzle structure for injecting the liquid into the bottle and for withdrawing the air therefrom.

Another object of the invention is the provision of a bottle filling apparatus having a 25 plurality of nozzle structures, whereby a plurality of bottles can be filled simultaneously, and said structures being adjustable relative to one another in order to accommodate the bottles when they are spaced different distances apart.

It is also within the scope of the invention to provide a bottle filling apparatus wherein the component parts are assembled in a novel 35 and efficacious manner, to enhance the utility and efficiency of the apparatus.

With the foregoing and other objects in view which will appear as the description proceeds, the invention resides in the combination and arrangement of parts and in the details of construction hereinafter described and claimed, it being understood that changes in the precise embodiment of the invention herein disclosed can be made with 45 in the scope of what is claimed without departing from the spirit of the invention.

The invention is illustrated in the accompanying drawings, wherein:—

Figure 1 is a view of the apparatus, portions being shown in section, some in elevation, and others being broken away, the device which is applied to the bottles being shown in section on the line 1—1 of Fig. 3.

Fig. 2 is an enlarged sectional detail on 55 the line 2—2 of Fig. 1.

Fig. 3 is a bottom plan view of the device which is applied to the bottles.

Fig. 4 is an enlarged end view of said device.

Fig. 5 is an enlarged detail of the reversing valve.

Fig. 6 is an enlarged sectional detail of the nozzle structure.

In carrying out the invention, there is provided a pair of nozzle structures, although 65 one or more than two can be used, and as far as the details of the nozzle structure is concerned, they have no particular bearing upon the use of a plurality of nozzle structures, and it will suffice to consider one of 70 said structures in detail only. Each of said nozzle structures embodies a head 1 having a vertical bore or chamber 2 therein and a nipple or port 3 at the upper end of said chamber and of smaller diameter, there being a tapered or conical seat 4 at the basal end of the nipple 3. The head 1 is provided at one side with an opening or port 5 communicating with the chamber 2, and the lower end of the head has a counter bore 6 80 surrounding the lower end of the chamber 2. A depending nozzle 7 is provided with an enlarged upper end 8 threaded within the counter bore 6, and a vertical nozzle 9 of smaller diameter than the nozzle 7 extends 85 axially through said nozzle, the lower end of the nozzle 9 projecting from the outer nozzle 7. The upper end of the inner nozzle 9 projects above the upper end of the nozzle 7 within the chamber 2, and is provided with 90 an enlarged tapered or conical portion 10 seated tightly within the seat 4, to provide a fluid tight joint, and whereby the nozzle 9 communicates with the nipple or port 3. The nozzle 7 communicates with the chamber 95 2 and its port 5, and the nozzle 9 is provided within the nozzle 7 with longitudinal radial ribs 11 contacting with the nozzle 7, to hold the two nozzles concentric, and the upper ends of the ribs 11 have shoulders 12 100 seating upon the upper end of the nozzle 7, whereby when the nozzle 7 is threaded home, it will raise the nozzle 9 and seat the upper end thereof tightly within the seat 4. The nozzle 9 is thus supported by the nozzle 7, 105 and the lower ends of the ribs 11 project out of the nozzle 7 and extend to the enlarged tapered or frusto-conical lower protruding end 12' of the inner nozzle. A packing washer 13 is fitted upon the nozzle 7 and 110

rests against the lower end of the head 1, in order that when the nozzles 7-9 are inserted into the neck of a bottle B, the washer or gasket 13 will seat upon the upper end of the neck, to provide a tight seal, thereby closing the mouth of the bottle to the atmosphere.

10 A horizontal tube or pipe 14 has one end threadedly or otherwise engaged within the port 5 to communicate with the chamber 2, and an elbow 15 is engaged upon the nipple 3, and has connected thereto one end of a horizontal tube or pipe 16 disposed above and parallel with the pipe 14. The elbow 15 has removable plugs 17, which when they 15 are removed enable the corresponding parts to be cleaned out by inserting a brush or other suitable implement.

20 There are two pipes 16 and two pipes 14 for the two nozzle structures, and said pipes extend rearwardly from said structures, and are provided at their rear ends with balls 18 seated in the sockets 19 in the ends of the diverging branches 20 of upper and lower Y-shaped couplings 21 and 22, respectively. 25 Nuts 23 surrounding the balls 18 are threaded upon the ends of the branches 20, for holding the balls 18 seated, and packing rings 24 are disposed within the nuts 23 and embrace the balls 18 for providing fluid tight joints, to prevent leakage. The ball and socket connections between the pipes and couplings enable the two nozzle structures to be moved toward and away from one another.

30 35 As a means for manipulating the nozzle structures, a stay bolt 25 is engaged with the crotch portions of the couplings 21 and 22, and also secures in place upon the upper coupling 21, the doubled strap 26 which is 40 attached to the rear end of an upper longitudinal handle 27. The forward end of said handle is secured to a vertical transverse plate 28, and one of the heads 1 is secured rigidly, as at 29, to the rear side of said plate. A screw 30 is threaded into the forward side of the other head 1 and works within a horizontal slot 31 with which the plate 28 is provided, whereby the last mentioned head can be adjusted transversely to 45 and from the aforesaid heads, to space the nozzles different distances apart. When the screw 30 is tightened, the shiftable head 1 is clamped in place, and when the screw is loosened, said head can be adjusted transversely.

50 55 As a convenient means for shifting the movable head 1, a link 32 has one end engaging the screw 30 between the head thereof and the plate 28, to act as a washer, and its other end is pivoted to the upwardly projecting arm 33 of a lever which is fulcrumed, as at 34, through the plate 28, and which has a second upwardly projecting arm 35 in rear of said plate 28. The arm 35 is in such 60 65 a position that when the handle 27 is grasped

by the hand, the thumb or index finger can be used for swinging the arm 35, to adjust the movable head 1, as the device is applied to the bottles, whereby the nozzles can properly enter the bottle necks. When the lever 33-35 is moved in one direction it moves the heads 1 away from one another, and when the lever is reversed, the heads are moved closer together. This provides convenient means for adjusting the nozzles as 75 they are applied to the bottles.

Attached to the couplings 21 and 22 is a reversing or four-way valve, embodying a casing or body 36 having a pair of nipples 37-38 at one end connected to the respective couplings 21 and 22, and having a pair of nipples 39-40 at its opposite end. The body 36 is provided between its ends with a transverse bore 41 in which is mounted for rotation a spigot or plug 42, there preferably being suitable means for limiting the rotation of said spigot whereby it cannot be moved too far in either direction. This spigot also has a handle or finger piece whereby it can be operated easily. The body 36 is provided with bores or passages 43, 44, 45 and 46 converging from the respective nipples 37, 38, 39 and 40 to the bore 41, the passages 44 and 46 being in alinement, and the passages 43 and 45 also being in alinement. The alining passages 43-45 and 44-46 are disposed in spaced planes adjacent the bore 41, as seen in Fig. 5, and the spigot 42 is provided with a pair of diametrical passages 47 and 48 arranged in 10 spaced planes and also arranged in crossed relation. The passage 47 is adapted to register with the passages 44 and 46, when the passage 48 registers with the passages 43 and 45. The spigot 42 is provided upon its periphery with opposite oblique grooves or channels 49 and 50, in order that when the passages 47 and 48 are moved out of registration with the passages with which they communicate, the channels 49 and 50 will reverse the flow of fluid. Thus, the channel 49 is adapted to communicate with the passages 45 and 44, when the channel 50 establishes communication between the passages 43 and 46. Thus, when the spigot 42 is in one position, the passages 43 and 45 are in communication and the passages 44 and 46 are in communication, and when the valve is rotated to the other position, the passages 44 and 45 and the passages 43 and 46 are 110 in communication. This provides convenient and simple means for reversing the flow of the fluid to and from the nozzles.

Connected to the nipple 39 to communicate with the passage 45, is a hose 51 which 125 communicates with a tank containing the liquid with which the bottles are to be filled, and said tank is preferably disposed at a lower level, whereby the liquid must be raised in passing to the nozzles. A hose or 130

flexible conductor 52 is connected to the nipple 40, and its remote end extends through the cover 53 of a jar or vessel 54. A pipe or tube 55 also extends through the 5 cover 53, and is connected to a suitable pump (not shown), for creating an air suction. The tubes 52 and 55 communicate with the upper portion of the jar 54, and said jar provides a trap for catching any liquid 10 which is sucked from the nozzles by the air suction.

As a means for preventing the liquid from being sucked from the jar 54 into the pump should the jar become filled with liquid, a 15 vertical tube 56 is engaged through the cover 53 and has its upper end closed, and said tube is provided above the cover 53 with a lateral opening 57 normally closed by a sleeve valve 58 slidably upon the tube 20 56. A stem 59 has its upper end secured to the valve 58 through the opening 57, and has attached to its lower end within the jar 54 a float 60 of any suitable sort.

Should the jar 54 become filled with the 25 liquid, up to a level in which the float is disposed, the float will be raised by the liquid, and this upward movement of the float will be transmitted by the rod or stem 59 to the valve 58, so that said valve will be 30 raised. This will uncover the opening 57, and permit air to flow into the jar 54 from the atmosphere, and the air suction created by the pump connected to the pipe 55 will be relieved by the air flowing into said jar, 35 and the air suction will therefore not extend through the tube or hose 52, which will check the further operation of the apparatus, until the jar 54 is emptied.

In operation, supposing the spigot or 40 valve 42 to be disposed as illustrated in Fig. 1, so that the hose 52 is in communication with the pipes 14, while the hose 51 is in communication with the pipes 16, the air suction will extend into said pipes 14, and 45 from thence into the chambers 2 of the two heads 1. The air suction will therefore extend through the outer nozzles 7 thereby withdrawing the air from the bottles, tending to create vacuums within the bottles, and 50 the suction will therefore extend through the inner nozzles 9 into the pipes 16 and hose 51. As a result, the liquid will be sucked from its tank or reservoir, and will flow through the hose 51 into the pipes 16 55 and from there downwardly through the nozzles 9 into the bottles centrally thereof. In this manner, the air in being sucked from the bottles, will draw the liquid thereinto, it being kept in mind that the washers or 60 gaskets 13 seal the spaces between the heads 1 and necks of the bottles. As soon as the liquid within the bottles rises to a level in which the lower ends of the nozzles 7 are disposed, air can no longer be sucked from 65 the bottles, which prevents the further fill-

ing of the bottles, and the liquid will then be sucked into the pipes 14 and hose 52, being caught by the jar 54 if the flow is continued too long. Thus, by providing nozzles of different lengths, the amount that the 70 bottles are filled can be controlled, since the bottles will not be filled at a level appreciably above the lower ends of the nozzles 7 when said nozzles are used as the air suction nozzles. When the liquid flows from the 75 nozzles 9 it passes downwardly centrally within the bottles, and the air passes upwardly adjacent the sides of the bottle and neck in passing to the annular space between the two nozzles.

With foamy liquids, it is preferable to discharge the liquid from the nozzle 7 into the bottle, and to use the inner nozzle 9 as the air suction nozzle. This is accomplished by reversing the valve 42 so that the 80 liquid supply hose 51 will now communicate with the pipes 14, while the air suction hose 52 will communicate with the pipes 16. Air will now be sucked from the bottle by way of the nozzle 9, and the liquid will therefore 85 flow into the bottle from the nozzle 7. The liquid in flowing from the nozzle 7 will be spread or deflected by the end 12' of the nozzle 9 so as to spray against the side walls of the body or neck of the bottle, whichever 90 is the case, and the liquid will run down the sides of the bottle, thus avoiding the splashing which occurs when the liquid flows into the bottle from the central nozzle, and consequently the foaming of the liquid is reduced 95 to a minimum. By operating the spigot or valve 42, the flow of air and liquid can be reversed instantly, without changing any of the 100 hose connections.

As soon as the nozzles are lifted from the 105 bottles, it is evident that even if the air suction is continued, the air suction nozzles will suck the air from the atmosphere, thus preventing the further discharge of the liquid instantly, but as soon as the nozzles 110 are applied to the new bottles, the flow of liquid is started immediately, thus eliminating the use of valves or other devices for this purpose.

An important advantage of the present 115 apparatus, is the fact that should the same be applied to a broken bottle, air will be admitted through the fracture of the bottle, thereby preventing the establishment of a partial vacuum within the bottle, so that no 120 liquid will flow into the bottle. This prevents the waste of liquid. Another advantage of the nozzle structure is the fact that the foaming of the liquid is reduced to a minimum and the surplus foam is sucked 125 off with the air and is caught within the trap or jar 54, the bottle thereby being rid of foam. The nozzle structure can be used conveniently with bottles any size and number seated on a table, tray or other support. 130

The present device can also be used in connection with various liquids, not requiring a separate apparatus for each liquid, and the nozzle devices can be applied to different styles and sizes of bottles from the smallest to the largest. No valves need be operated for controlling the flow of liquid into the bottles, thereby saving time and trouble, and the tank or vessel containing the liquid can be seated on the floor, and need not be raised.

Having thus described the invention, what is claimed as new is:

1. A filling apparatus embodying a pair of concentric nozzles, air suction and liquid supplying conductors, and means establishing communication between said nozzles and conductors and having reversing means thereby to connect the air suction conductor with either nozzle and the liquid supplying conductor with the other nozzle.

2. A filling apparatus embodying a pair of concentric nozzles, the inner nozzle protruding from the outer one and having means at its protruding end for spreading a liquid discharge from the outer nozzle, air suction and liquid supplying conductors, and means connecting said nozzles and conductors and including a reversing valve whereby either of the nozzles can be connected to the air suction conductor while the other nozzle is connected to the liquid supplying conductor.

3. A filling apparatus embodying a nozzle structure applicable to a vessel, liquid supplying means connected to said structure, an air suction conduit connected to said structure, a vessel interposed in said conduit for catching any liquid sucked into said conduit, means for admitting air from the atmosphere into said conduit, and a float in the last mentioned vessel for operating the last mentioned means when said vessel becomes filled with liquid.

4. A filling apparatus embodying a head having a chamber and a seat, an outer nozzle attached to the head to communicate with said chamber, and an inner nozzle extending through the outer nozzle, the outer nozzle holding the inner nozzle in place with one end against said seat, the head having ports communicating with said end of the second mentioned nozzle and with said chamber.

5. A filling apparatus embodying a head having a chamber, a lateral port communicating with said chamber, a port at one end of said chamber, and a tapered seat adjacent the second mentioned port, an outer nozzle threadedly engaged with the head at the other end of said chamber, and an inner

nozzle projecting through the outer nozzle 60 and having one end provided with a tapered portion fitted in said seat, the inner nozzle having longitudinal ribs contacting with the outer nozzle to hold the nozzles concentric, and said ribs having shoulders engaging the threaded portion of the outer nozzle to hold the inner nozzle in place.

6. A filling apparatus embodying a pair of nozzles to project into a vessel, means for sealing the vessel, liquid supplying means 70 connected to one nozzle, and air suction means connected to the other nozzle and having means for catching any liquid sucked thereinto, and means for admitting air from the atmosphere to the catching means when 75 the catching means become filled with liquid.

7. A hand operated filling apparatus embodying heads movable to and from one another and having depending entering nozzles, a handle for manipulating said heads, 80 and means for moving said heads toward and away from one another and operable by a hand grasping said handle.

8. A hand operated filling apparatus embodying a plate, a handle attached to said 85 plate for manipulating it, a pair of heads carried by the plate and having depending entering nozzles, one of the heads being movable toward and away from the other, and means carried by said plate connected to the 90 movable head and operable by a hand grasping said handle for moving said head.

9. A filling apparatus embodying a plate, a handle attached thereto, a head carried by said plate, said plate having a slot, a second head, a screw working in said slot and threadedly engaging the second mentioned head, said heads having depending bottle entering nozzles, a lever carried by the plate and adapted to be operated by a hand grasping said handle, and a link connecting said lever and screw.

10. A filling apparatus embodying a pair of laterally spaced heads having depending concentric nozzles, vertically spaced horizontal pipes connected to each head to communicate with the nozzles, and a pair of vertically spaced Y-shaped couplings, the upper and lower pipes having ball and socket joints with the branches of said upper and lower couplings, respectively.

In testimony that I claim the foregoing as my own, I have hereto affixed my signature in the presence of two witnesses.
